UNITED STATES PATENT OFFICE

135,915

DESIGN FOR A SUPPORT FOR A TABLE TENNIS NET

Philip C. P. Booty, Chicago, Ill.

Application February 1, 1943, Serial No. 109,401

Term of patent 7 years

To all whom it may concern:

Be it known that I, Philip C. P. Booty, a subject of the King of Great Britain, residing at Chicago, in the county of Cook and State of Illinois, have invented a new, original, and ornamental Design for a Support for a Table Tennis Net, of which the following is a specification, reference being had to the accompanying drawing, forming part thereof.

In the drawing—

I claim:

The ornamental design for a support for a table tennis net, substantially as shown.

PHILIP C. P. BOOTY.
